UNITED STATES PATENT OFFICE.

JOSEPH JURAS, OF NEW YORK MILLS, NEW YORK.

ASH-SIFTER.

1,186,003.

Specification of Letters Patent.

Patented June 6, 1916.

Application filed October 11, 1915. Serial No. 55,257.

To all whom it may concern:

Be it known that I, JOSEPH JURAS, a subject of the Emperor of Austria-Hungary, residing at New York Mills, in the county of Oneida and State of New York, have invented certain new and useful Improvements in Ash-Sifters, of which the following is a specification.

This invention relates to certain new and useful improvements in ash sifters.

The primary object of this invention is the provision of an inexpensive device in the form of an ash sifter for house-hold use adapted for easy operation.

A further object of the invention is to provide an ash sifting device especially adapted for house-hold use being easily operated when desired for sifting ashes, the parts thereof being readily separable when desired 20 to remove the cinders or clean the device.

A still further object of the invention is to provide a swinging sifting frame adapted for holding an ash container and to impart a sudden jar to the latter during each 25 manual reciprocation thereof.

With these general objects in view and others that will appear as the nature of the invention is better understood, the same consists in the novel combination and arrangement of parts hereinafter more fully described, illustrated in the accompanying drawings, and pointed out in the appended 30 claims.

In the drawings forming a part of this 35 application and in which like-designating characters refer to corresponding parts throughout the several views:—Figure 1 is a vertical longitudinal sectional view of the device, and Fig. 2 is a top plan view thereof 40 with the cover broken away.

Referring more in detail to the drawings, a supporting frame is provided having four corner posts 10 connected together by opposite pairs of end rails and side rails 11 and 45 12 respectively positioned adjacent the lower and upper ends of the said posts.

A shiftable plate 13 is swingingly mounted between the upper side rails 11 of the said frame by means of oppositely positioned cranks 14 which are journaled in bearing blocks 15 positioned adjacent the corners of the plate 13 and upon the lower side thereof. The said plate 13 is provided with a circular central opening 16 adapted 55 for the reception of a removable ash container such as the metallic receptacle 17, a

depending spider 17' being carried by the plate 13 beneath the opening 16 upon which the receptacle 17 is arranged. An annular flange 18 is arranged within the receptacle 60 17 spaced from the top thereof and adapted to support a bowl shaped sieve or sifting basket 19 of foraminous formation adapted for the direct reception of the ashes. A closure cover 20 is provided for the receptacle 17, while the basket 19 is provided with opposite handles 21 by which the same may be readily removed from the receptacle when desired.

An operating means is provided for the 70 device consisting of a resilient angular lever 22 having a horizontally arranged handle 23 at the upper end of the vertical outer portion 24 thereof, while the main portion of the handle is provided with an oval shaped 75 ring 25 which encircles the plate opening 16 as well as the receptacle 17, when the same is positioned therein, the said ring being formed of flat metal and slidably positioned upon the upper face of the plate 13. A 80 finger 26 is provided at the rear end of the ring 25 and has a longitudinal slot 27 therein corresponding to a slot 28 in the handle 22 adjacent the forward side of the said ring and headed screws 29 are carried adjacent 85 the front and rear edges of the plate 13 and extend through the said slots 27 and 28 for retaining the said ring 25 slidably positioned upon the said plate 13. It will thus be seen that with the plate 13 shiftable suspended 90 upon the cranks 14 and with the receptacle 17 removably positioned through the ring 25 and the plate openings 16, the cover 20 of the receptacle may be readily removed and ashes deposited into the basket 19. By 95 grasping the handle 23 and pulling same outwardly, one end wall of the slots 27—28 will be forcibly brought into engagement with the screws 29 thereby imparting a sudden jar to the plate 13 as well as the ash receptacle 17 and sieve carried thereby. When the outward pull on the handle is relieved the plate 13 swings back, and as the handle is pushed inwardly it slides on the plate and the other ends of the slots 27—28 100 are brought forcibly into engagement with the screws 29. The ashes in the basket 19 will be thus considerably agitated and shaken up by the repeated reciprocations and jarring of the plate 13 allowing the 105 smaller particles to fall within the receptacle 17, so that the ashes will be completely 110

sifted and the cinders will remain in the basket 19, which may be removed from the receptacle 17. The receptacle may then be emptied and the device is ready for further 5 operation.

While the form of the invention herein shown and described is what is believed to be the preferred embodiment thereof, it is nevertheless to be understood that minor 10 changes may be made therein without departing from the spirit and scope of the invention as claimed.

What I claim as new is:—

1. An ash sifter comprising a supporting 15 frame having side rails, cranks arranged within the frame with their ends journaled in said side rails, a plate carried by said cranks and having a central opening, an ash receptacle mounted in said opening, a support 20 for said receptacle depending from the plate, a sifting basket removably-mounted

in said receptacle, and an operating handle having a slidable connection with said plate for jarring the latter as the handle is reciprocated.

25

2. An ash sifter comprising a frame, depending cranks oppositely journaled through the said frame, a swinging plate journaled between the said cranks and having a central opening therethrough, a spider carried by the said plate beneath the said opening, an ash receptacle positioned through the said opening upon the said spider, a foraminous basket removably positioned within the said receptacle, an oval ring slidably mounted 35 upon the said plate surrounding the said receptacle, stop retaining means for the said ring carried by said plate, and manual reciprocating means carried by the said plate.

In testimony whereof I affix my signature. 40

JOSEPH JURAS.
